UNITED STATES PATENT OFFICE.

ISAAC M. PECK, OF TIFFIN, OHIO, ASSIGNOR OF ONE-HALF TO RALPH H. MAY, OF TIFFIN, OHIO.

NUT-LOCK.

1,074,196.

Specification of Letters Patent. Patented Sept. 30, 1913.

Application filed August 30, 1912. Serial No. 717,905.

To all whom it may concern:

Be it known that I, ISAAC M. PECK, a citizen of the United States, residing at Tiffin, in the county of Seneca, State of Ohio, have 5 invented certain new and useful Improvements in Nut-Locks; and I do hereby declare the following to be a full, clear, and exact description of the invention, such as will enable others skilled in the art to which 10 it appertains to make and use the same.

The present invention is directed to improvements in nut locks, the same being so constructed that the nut will be prevented from becoming accidentally removed from 15 the bolt.

A further object of the invention is to provide a nut lock, which is exceedingly simple in construction and one which may be manufactured at a minimum cost.

With these and other objects in view, this 20 invention resides in the novel features of construction, formations, combinations and arrangements of parts to be hereinafter more fully described, claimed and illustrated 25 in the accompanying drawing, in which:—

Figure 1 is a side elevation of the device. Fig. 2 is a top plan view. Fig. 3 is a transverse sectional view through the nut and bolt, showing the key in elevation. Fig. 4 30 is a side elevation of the key.

Referring to the drawing, the numeral 1 designates a bolt, the same being provided along its threaded portion with longitudinal grooves 2. The nut 3 is provided with the 35 usual bolt opening 4 having opening there into a transverse bore 5 a similar bore 6 being also formed in the nut, the latter bore having its inner end 7 provided with a perforation 8. The nut is further provided 40 upon one side with a straight groove 9, said groove extending from the outer end of the bore 5 to the inner end of the bore 6. The key 10 consists of an arm 11 which operates in the bore 6 and has one of its ends passing 45 through the perforation 8, said end terminating in a lateral extension 11', said extension in turn terminates in a projection 12, which is arranged parallel to the arm 11, and operates in the bore 5 for engaging the 50 grooves 2 formed in the bolt 1.

Formed in one side of the nut and diametrically opposite the groove 9 is a beveled groove 13, the same being for the purpose of receiving the inclined end 14 of the key 10 which is correspondingly inclined to fit 55 the groove 13. Rigidly connected to the arm 11 and near the end 14 thereof is a sleeve 15, which engages one end of a coil spring 16, the other end of which bears against the inner end of the bore 6, said 60 spring surrounding a portion of the arm 11 and serves to hold the end 14 displaced from the groove 13 and the projection 12 normally in engagement with one of the grooves 2 formed in the bolt. Thus it will be seen 65 that the nut 3 may be threaded upon the bolt in the usual manner, and the projection 12 will engage the grooves of the bolt to prevent reverse rotation of the nut. When it is desired to remove the nut it is only necessary that the end 14 be engaged and forced in the groove 13, whereupon the projection 12 will disengage the bolt, thus permitting the nut to be removed.

What is claimed is:—

In a nut lock the combination with a longitudinally grooved bolt, of a nut having a bore opening into the bolt opening, a second bore formed in the nut, an inclined groove formed in one side of the nut, a key consisting of an arm, said arm being operable in the second named bore, and having one of its ends bent for engagement in the inclined groove, a sleeve fixed to the arm and held thereon by the bent end of said arm, a coil 80 spring surrounding a portion of the arm and having one of its ends engaged by the sleeve, the other end of said arm having a lateral extension which terminates in a projection 85 adapted for operation in the first named 90 bore for engaging the grooves in said bolt.

In testimony whereof I affix my signature in presence of witnesses.

ISAAC M. PECK.
